UNITED STATES PATENT OFFICE.

JOHN HENRY JOHNS, OF NATIONAL MILITARY HOME, KANSAS.

ELECTRIC ALARM AND WATER-GAGE.

SPECIFICATION forming part of Letters Patent No. 394,491, dated December 11, 1888.

Application filed February 4, 1888. Serial No. 263,038. (No model.)

To all whom it may concern:

Be it known that I, JOHN HENRY JOHNS, of National Military Home, Leavenworth county, Kansas, have invented a new and useful Improvement in Electric-Alarm Water-Gages, of which the following is a specification.

My invention relates to a means whereby either extreme high or extreme low water in a tank or boiler causes the automatic sounding of an electric alarm.

In the accompanying drawings, Figures I, II, and III, respectively, are a side elevation, a vertical section, and a top view of the mechanism by which an extreme rise or an extreme fall of the water within the tank or boiler automatically closes the electric circuit of a magneto-bell. Fig. IV is a section on the line IV IV.

1 may represent the upper part of a tank or boiler. 2 is a float, and 3 is the float-stem passing through a stuffing-box, 4, in the boiler. For simplicity of illustration the float is represented attached direct to the stem 3; but such float and stem may, obviously, be coupled to opposite ends of a customary float-lever, if desired.

Attached to the top of the said stem is a rod, 5, of wood or other non-conducting material. Fastened by means of set-screws 6 at any desired heights on the rod 5 are two conductors, 7 8, which in ordinary conditions of the water are out of contact with the "brushes" + and - of an electro-magnetic sounder-circuit. Such inert condition of the apparatus is seen in Fig. I. Such extreme elevation or depression of the rod 5 as to bring a conductor in contact with the brushes for low-water alarm is seen in Fig. II. The said brushes are each one fastened to one of two wedge-shaped plugs or insulators, 9, of any suitable non-conducting material, secured in dovetail notches 10 of upper plate, 11, of the frame 12, whereby they may be adjusted horizontally by movement vertically to regulate the distance between the brushes.

13 14 represent metallic sleeves, which, in-

closing the pillars 15 of the said frame, rest upon the lower plate, 16, thereof. One of these sleeves has a hook-formed catch or lateral projection, 17, which may be engaged under the lower conductor, 7, as shown in Fig. I, or under a union or collar, 18, so as to prevent the float striking the bottom of the boiler during inspection or repair thereof.

The stuffing-box 4 is preferably provided with a stop-cock, 20, whose spigot 19, in the position shown in Figs. I and II, permits the traverse of the stem 3. On removal of said stem for any purpose a quarter-turn of said spigot, by closing the stuffing-box passage after said removal of the float-stem, prevents escape of steam at that part.

Associated with the rod 5 may be a customary scale of inches for visual indication of the height of water in the boiler or tank. This I arrange by securing to the collar 18 a pointer, 22, and upon the sleeve 14, by means of bands or otherwise, a scale, 23. These securing-bands may be clamped by thumb-nuts, which will facilitate vertical adjustment of the scale.

I claim as new and of my invention—

1. The combination of the float-stem 3, upper non-conducting portion, 5, carrying the conductors 7 8, and a union or collar, 18, substantially as and for the purpose set forth.

2. In combination with the float-stem 3 and the lower conductor, 7, the sleeve 13, having the catch 17, substantially as and for the purpose set forth.

3. The combination of the float - stem mounted in the frame and movable vertically, a collar on said stem, and a support, substantially as described, supported on the frame and adapted to move into engagement with said collar, for the purpose set forth.

In testimony of which invention I hereunto set my hand.

JOHN HENRY JOHNS.
